UNITED STATES PATENT OFFICE.

JOHN STORY, OF GODERICH, ONTARIO, CANADA.

CARPET-STRETCHER.

SPECIFICATION forming part of Letters Patent No. 387,930, dated August 14, 1888.

Application filed April 2, 1888. Serial No. 269,409. (No model.)

To all whom it may concern:

Be it known that I, JOHN STORY, a subject of the Queen of Great Britain, residing at the town of Goderich, in the county of Huron and Province of Ontario, Canada, have invented a new and useful Carpet-Stretcher, (for which no patent has yet been obtained or applied for in any country,) of which the following is a specification.

10 My invention relates to the combination of two wooden bars, one of them having at one end the carpet-stretcher points, similar to those ordinarily in use, and at the other end a reduced part with a slot in it, in which it is intended that a curved toothed or ratchet bar shall work, and the other bar having at one end a slender metal prong or needle and at the other end a part with a slot in it, as in the first bar. The two bars are connected together at 20 the joints by a pin forming a male and female joint, so that the machine may be extended or closed, and so that the prong being inserted in a floor or other surface and held in a slanting position, the stretcher-points may be moved 25 easily backward or forward by raising or depressing the center, where the two bars are joined together. With the above is also combined a curved toothed or ratchet bar connected by a pin with the inside of the slot below the joint in the pronged bar and working 30 easily up and down in the opposite slot, so that when it is allowed to drop against the base of the last-named slot, such base being beveled so as to form an edge or angle on the 35 inside, any of the teeth in the toothed or ratchet bar will lock with the beveled edge of the slot and prevent the center of the machine from being raised, and when being used for carpet-stretching will hold it rigid in any position desired.

The accompanying drawings show the mechanism of the invention. Figure 1 is a drawing of the carpet-stretcher partially extended. Fig. 2 is a drawing of the same closed. Fig. 3 is a plan of the carpet-stretcher bar of the machine with male joint and slot beveled at the base on the upper end of the bar. Fig. 4 is the pronged bar with joint and slot at the upper end. Fig. 5 is a drawing of the curved toothed or ratchet bar.

In the drawings similar letters refer to similar parts throughout the several views.

A is the bar, having carpet stretcher points B at the lower end and the reduced part at upper end with slot *a'* in it, the base of which 55 slot is beveled from *g* to *h*.

C is the pronged bar having the prong or needle D at the lower end and a part with a slot, *e*, at the upper end. When these two bars are to be united, the slotted end *a'* of the one 60 fits into and between the slotted end *f* of the other, and then these two bars are connected by a pin at *a* in such manner that the prong D and stretcher-points B will work easily backward and forward from the center, and so that 65 the machine may be extended, as in Fig. 1, or closed, as in Fig. 2, of the drawings.

E is the curved toothed or ratchet bar connected with inside of the slot at *f* by a pin, so that it will work easily up and down inside 70 the opposite slot from *a* to *g*, and so that it may be allowed to fall upon the beveled edge of the base of the slot at *g*, and any of the teeth will lock with such edge and prevent the center of the machine from being raised.

In working the machine in the operation of laying carpets the metal prong or needle D is passed through the carpet and into the floor or other surface in a slanting position, the metal carpet-stretcher points being then applied to 80 the carpet in the usual way, and the center of the machine being depressed, the points are pushed forward, drawing the carpet with them as far as the length of the prong D will allow, the latter being sufficiently small to allow the 85 carpet to move up on it without injury. The tooth-bar is then lowered so that one of the teeth will lock with the beveled edge of the base of the slot at *g* and will hold the machine rigid until the carpet can be tacked or otherwise secured by the operator.

I am aware that prior to my invention carpet-stretchers and carpet-stretcher points have been in use.

I claim—

1. The herein-described carpet-stretcher, composed of the two bars A and C, the one having the slotted end *a'* and the other a slotted end, *e*, so that their ends form a male and female joint, the one part fitting into the other 100 and the two pivoted together by a pin, and the curved ratchet-bar E, pivoted in the slot *f*, substantially as shown and described.

2. A carpet-stretcher composed of two mem-

bers, A and C, the first having at its lower end the stretcher-point B and at its upper the slotted part a' , the latter having the needle-point D at its lower end and the slotted part 5 e at the other, the two slotted parts forming a male and female joint, the said male and female joint fitting the one part upon and over the other and the two hinged together by a

pin, and the ratchet-bar E, pivoted in one of the slotted joints and engaging in the beveled 10 edge of the opposite slotted joint, all substantially as and for the purposes set forth.

JOHN STORY.
